CLAIM

The ornamental design for a display panel portion with a computer icon, substantially as shown and described.

DESCRIPTION

The single FIGURE is a front view of a display panel portion with a computer icon, showing our new design.

The outermost broken lines showing a display panel portion are included for the purpose of illustrating portions of the article and form no part of the claimed design. The broken line showing of a circle forms no part of the claimed design.

1 Claim, 1 Drawing Sheet
